UNITED STATES PATENT OFFICE.

DOSSA E. ROHRER, OF CHARLOTTE, NORTH CAROLINA.

CABLE CLAMP.

Application filed September 6, 1928. Serial No. 304,327.

This invention relates to a cable clamp made in various types and sizes for use on cables of any size, and also adapted to be used on any type of strain insulator as dead-end, for turning a corner, for holding a strand of a cable and at the same time providing a means for the cable to pass through the clamp to any desired apparatus without the necessity of making a splice. This cable clamp may be used on either insulated or bare cable.

An object of my invention is to provide a cable clamp, which is of straight line design and being adapted to put the strain from the cable on a direct line with the insulator eye.

Another object of my invention is to provide a cable clamp which is adaptable to any type of strain insulator.

Another object of my invention is to provide a cable clamp by means of which a full clamp effect may be provided by means of having guides on each side, which are adapted to hold the cable in its original shape and to prevent the cable strands from pushing out at the sides of the clamp, while at the same time providing corrugations in both portions of the clamp in the groove in which the cable is adapted to be secured, said corrugations staggered with relation to each other so as to reduce to a minimum the possibility of the cable slipping.

Another object of my invention is to provide a cable clamp which is so designed that the strain from the clamp bolts is all transferred against the sides of the cable, and in which the bolt heads are locked so that the bolts may be tightened by the use of one wrench only, and which is provided with a protective guide on each end of the clamp to prevent the cutting of cable strands due to vibration, and in which there is also provided a bend-forming bridge on the forward end of the clamping part which automatically bends the cable as the clamp is tightened around it.

Another object of my invention is to provide a cable clamp having a minimum width with maximum strength so as to provide maximum clearance between phases when installed on standard phase spacings.

Some of the objects of my invention having been stated, other objects will appear as the description proceeds when taken in connection with the accompanying drawings, in which:

Figure 1 is a side elevation of one of my cable clamps;

Figure 2 is a plan view of my cable clamp looking downward in Figure 1;

Figure 3 is a top plan view of my cable clamp looking upward in Figure 1;

Figure 4 is a bottom plan view of the main portion of my cable clamp with the lower portion thereof removed and showing the inner face thereof;

Figure 5 is a view of the interior face of the shorter portion of my cable clamp;

Figure 6 is a side elevation showing a form of my cable clamp attached to an insulator and used as a dead-end;

Figure 7 is a view similar to Figure 6 with the cable being adapted to be passed on beyond the insulator;

Figure 8 shows the use of my cable clamp for the installation of switches, transformers, step-up stations, etc.

Referring more particularly to the drawings the numeral 10 indicates the base portion of my cable clamp which has the forked portions 11 and 12 in which the bolt 13 is adapted to be placed for securing the same to an insulator or other object. This portion 10 has the side portions 14 and 15 with the central rib 16 on the top side thereof and the bend-forming bridge 17 extending from the rib 14 to the rib 15. The clamping portion of the member 10 is indicated by the numeral 18 and this has the longitudinally and centrally disposed groove 19 therein with the ribs 20 running transversely of the groove, and spaced holes 21 are provided on each side of the groove with the ribs 22 being disposed transversely and running to the side wall of the groove 19 and the upstanding projections 23 are provided on each side of the groove 19, which projections are adapted to pass through the holes 24 in the member 25, and the member 25 has the projections 26 which are adapted to project through the holes 27 in the member 18. The member 25 has the holes 29 through which the bolts 30 are adapted to pass, said bolts also being adapted to pass through the holes 21 in the member 18. The member 25 has the ribs 32 which are similar to the ribs 22 on the member 18 which serve for reinforcing purposes, and similar ribs 33 are provided on the lower side of the member 25, which is the upper side in Figure 1 and the portion 18 has the transverse ribs 33^a on the upper side thereof, which is the lower side in Figure 1 which ribs serve for reinforcing purposes and also serve to prevent the heads of the bolts 30 from turning.

These bolts 30 have the nuts 35 thereon with the lock washers 36 and the ends of the portions 18 and 25 are rounded as at 36^a and 37 to prevent the strands of the cable from being cut, and on the opposite end of the member 25 from the point 37 the groove 38 is hollowed out as at 39, which portion cooperates with the bend-forming bridge 17 to automatically bend the cable and to prevent the same from being cut as would be the case were the ends of the clamping portions not rounded as illustrated.

The member 25 which has the groove 38 therein, also has the transverse ribs 40 which are staggered with relation to ribs 20 so as to give a maximum clamping effect upon the cable.

In Figure 4 I have shown the clevis portion formed from the members 11 and 12 to be disposed at right angles to the clevis portions in Figures 1, 2 and 3, which is done for the purpose of illustrating that the clevis portion of the cable clamp may be disposed at any desired angle with the relation to the clamping means proper in order to fit the particular insulator or in order to suit the requirements under which the cable clamp is desired to be used, which clevis portion is indicated by the numeral 41 in Figure 4.

In Figures 6, 7 and 8 I show a form of my cable clamp in which there are only three sets of bolts instead of four as illustrated in Figures 1 to 5, and in which case the projections on one of the members 18 or 25 will be eliminated as these projections, as indicated by the numeral 23 or 26 are adapted to fill the spaces between the bolts 30 and to prevent the cable from spreading between the bolts when it is firmly clamped in my device, and in Figure 6 I show the insulator 42 in which my cable clamp 43 is secured with the cable 44 passing therethrough, and this form of illustration shows the manner in which any size of my cable clamp may be used when the cable is desired to be dead-ended, while in Figure 7 the structure is the same, but it shows the cable 44 being passed downwardly where it can be led to any desired point. In Figure 8 I have shown two of my cable clamps secured to suitable insulators 45 and 46, which in turn are secured to the insulator member 47 which is secured to the cross arm 48 and co-operating with the insulators 50 and 51 is the switch mechanism 52 with the cables 44 being passed through by cable clamps 43 and connected to the switch mechanism, it being understood that this switch mechanism is merely illustrative and may be discarded for substitution instead thereof the transformer, step-up station or any other desired arrangement.

By the construction of the above described, and especially in view of the re-inforcing ribs 22, 33 I obtain a structure which will transmit all of the clamping effect directly against opposite sides of the cable and which combines

maximum strength and minimum width so as to make my cable clamp very desirable in phase spacings, so as to provide a maximum clearance between the phases.

My cable clamp can be made of any desired material, but the preferred material may be stated as follows:

The main portion 10 together with the portion 18 is made of malleable iron, while the lower portion 25 is made of brass which eliminates the magnetic circuit and subsequent inductive heating when used on alternating current.

In the drawings and specification I have set forth a preferred embodiment of my invention, and although specific terms are employed, they are used in a generic and descriptive sense only, and not for purposes of limitation, the scope of the invention being set forth in the appended claims.

I claim:

1. A cable clamp comprising an elongated main portion having an eye for securing the same to a support, a longitudinal groove in the lower side thereof, transverse ribs in the groove, a plurality of aligned holes adapted to receive bolts and being disposed on each side of the groove, a plurality of upstanding projections in alignment with the said holes and disposed therebetween, a plurality of transversely disposed ribs, a bottom member having a longitudinally disposed groove therein, a plurality of transverse ribs in said groove and being adapted to occupy a point intermediate the transverse ribs in the base member or main portion, a plurality of aligned holes on each side of the groove adapted to receive bolts, a plurality of projections intermediate the said holes, the projections on one member being adapted to pierce holes in the other member and to fill the space between the bolts to prevent the cable from spreading when in clamped position.

2. A cable clamp comprising a main portion and a minor portion, aligned grooves in both portions and being longitudinally disposed with relation to the said portions, a plurality of aligned holes in the portions adapted to receive bolts, a plurality of projections on each portion disposed between the said bolts and being adapted to project thru holes in the other portion, a bend-forming bridge in the main portion adapted to cooperate with the rounded end of the groove in the minor portion to automatically form a bend in the cable as the same is clamped, and transversely disposed ribs on both sides of the said portions, said ribs being adapted to prevent the said bolts from turning and to also act as reenforcing elements.

3. A cable clamp comprising a main portion and a lower portion having coinciding longitudinally disposed grooves therein, means for securing the two portions around a cable, projections on each portion adapted

to penetrate holes in the other portion, an eye portion on the main portion for securing the cable clamp to any suitable support, said eye member being in alinement with the 5 central point of the cavity formed by the groove in which the cable is clamped.

4. A cable clamp comprising an elongated portion and a shorter portion adapted to be secured to the elongated portion by means of 10 bolts, longitudinally disposed alined grooves in the two portions, the ends of the grooves being rounded and a bridge in the elongated portion adapted to cooperate with the rounded portion of the shorter portion to form a 15 bend in the cable when the two portions are secured around a cable.

5. In a cable clamp, a main portion and an auxiliary portion a longitudinal groove in each of the portions, a plurality of bolts 20 adapted to penetrate both portions to secure the same around a cable and a plurality of projections on each of the portions adapted to penetrate holes in the other portion to fill the spaces between the bolts to prevent the 25 spreading of the cable when clamped in position.

6. In a cable clamp, two portions adapted to be secured to each other by means of rows 30 of alined bolts, coinciding alined grooves in each of the portions, a plurality of projections on each of the members filling the spaces between the bolts, means on the end of one of the members for securing the same to a support, the ends of the grooves being of 35 larger dimensions than the main portion thereof, and a bend-forming bridge located in close proximity to the end of the groove in one of the members adapted to cooperate with the end of the groove in the other member 40 to automatically bend the cable as the same is clamped by the two members.

7. In a cable clamp, a main portion and an auxiliary portion, a longitudinal groove in each of the portions, a plurality of bolts adapted to penetrate both portions and to secure the same around a cable, a plurality of 45 projections on one of the portions adapted to penetrate holes in the other portion, said projections being adapted to fill the spaces between the bolts to prevent the spreading 50 of the cable when clamped in position, and prevent one portion shifting its position with relation to the other portion.

8. A cable clamp comprising an elongated portion and a shorter portion adapted to be 55 secured to the elongated portion by means of bolts, longitudinally disposed alined grooves in the two portions, the ends of the grooves being rounded and a bridge in the elongated portion being adapted to cooperate with the 60 rounded portion of the shorter portion to form a bend in the cable when the two portions are secured around a cable, projections on one of the portions, holes in the other portion through which the projections are adapted 65 to fit when the two portions are secured around the cable.

9. A cable clamp comprising a main portion and an auxiliary portion, said portions having coinciding longitudinally disposed 70 grooves therein, means for securing the two portions around the cable, projections on one portion adapted to penetrate holes in the other portion, an eye portion on the main portion for securing the cable clamp to any suitable support, said eye member being in alinement with the central point of the cavity 75 formed by the groove in which the cable is clamped.

In testimony whereof I affix my signature.
